To all whom it may concern:

Be it known that I, Ramon Reachi, a citizen of the United States, residing in Santa Monica, county of Los Angeles, State of California, have invented a new, original, and ornamental Design for a Lamp, of which the following is a specification, reference being had to the accompanying drawings, forming part thereof.

Fig. 1 is a front perspective view of a lamp showing my new design;

Fig. 2 is a rear perspective view thereof, the outer cylinder being shown in raised position;

Fig. 3 is a plan view looking at the top of Fig. 2; and

Fig. 4 is a plan view looking at the bottom of Fig. 1.

The dominant features of my new design are shown in solid lines.

I claim:

The ornamental design for a lamp, as shown and described.
